PROGRAM DISTRIBUTION SYSTEM

Charles de Vriendt, Boulogne - Billancourt, France, assignor to Western Electric Company, Incorporated, New York, N. Y., a corporation of New York

Application July 8, 1933, Serial No. 679,499
In France November 19, 1932

10 Claims. (Cl. 179—2)

This invention relates to the provision of theatherphone, radio rediffusion, time and news service and the like to telephone subscribers via their telephone lines.

5 The object of the invention is to provide improved means for giving subscribers automatic access to such services and for giving the subscribers more complete control of the facilities at their disposal.

10 According to one feature of the invention, the subscribers are able to determine as desired, whether or not program or like service shall be interrupted by telephone calls.

15 According to a further feature of the invention, a subscriber provided with program service is enabled to obtain any desired program by manipulating a simple key and the usual substation dial, and to break down the program connection by means of the said key.

20 Further features of the invention will be apparent from the following description of one embodiment of the invention, with reference to the accompanying drawing which shows in Fig. 1, the equipment at the exchange individual to a 25 program subscriber, and in Fig. 2, the substation equipment.

The system shown provides the following facilities:

30 1. The subscriber himself can automatically connect with any theatherphone, radio rediffusion or similar programs.

2. Retain the possibility of originating calls on his line at any moment.

3. Receive telephone calls during the reception 35 of a program.

4. Have the possibility to prevent incoming calls during a program. In such a case, the called subscriber would be indicated as "busy" to his correspondent. It is possible to arrange the system so that such subscribers' lines can be connected to a phonograph indicating to the calling party that his correspondent is listening to a program and does not wish to be disturbed, or 45 the calls could be directed to an intercepting operator at the central office, who, in turn, could inform the subscriber later of the parties having called him during the time that he was listening to a program.

50 5. Means are also provided for metering the special service given to any entitled subscriber both according to time and to the class of service given.

55 6. A special signal either telephonic or coded is automatically sent to a subscriber calling for

special service indicating whether or not the wanted service is operating or not at that moment.

DESCRIPTION OF THE SYSTEM

I.—Modification to the subscriber's set

A simple key CT associated with the relay A and a retard coil R is equipped at the subscriber's station. With the operation of the relay a signal can be operated, either visual or audible, from a local source of current. The key CT is equipped at the substation so as to connect each of the line wires *a* and *b* through an impedance of 500 ohms to ground, the dial D remaining connected to the *a* wire.

II.—Equipment at the central office

A step-by-step switch S (or alternatively, a set of relays) of suitable capacity according to the maximum number of programs desired, is provided per line, with a group of relays *Tl*, *Lm*, *Lb*. A further relay *Nd* is only equipped when the subscriber desires to have his incoming calls held back during a program. The normal cut-off relay *Co* will have, instead of two break contacts, two change-over contacts. The normal line relay *L* should have a resistance of 500 ohms. A lamp *OL* can be added per line to detect a grounded *a* wire and to show also when key *CK*, common to a certain number of circuits, is actuated, which lines are listening to teleprograms. When any program service is available, the key *SK* corresponding thereto is operated.

METHOD OF OPERATION

Let it be assumed that the step-by-step switch S has 25 points which allows for about 20 different programs. The positions 1, 10 and 20 of the step-by-step switch will not be provided with connections for programs. The first position is used to discriminate whether or not the subscriber wants to have interrupted or uninterrupted program service. Positions 10 and 20 are not equipped to avoid interfering with other subscribers during the dialing of a tens digit, whereas, if these positions were equipped, due to the frequent dialing of the tens digits, such programs would be interfered with by the incidental clicks.

The numbering scheme for 20 programs would be made as follows:

There could be two numbering scheme tables, the first being for calling different programs with uninterrupted service, the second table being for

interrupted program service, permitting incoming telephone calls:

5	Uninterrupted program service	Interrupted program service with possibility of receiving incoming calls
10	1.1	2
	1.2	3
	1.3	4
	1.4	5
	1.5	6
	1.6	7
	1.7	8
	1.8	9
15	1.91	01
	1.92	02
	1.93	03
	1.94	04
	1.95	05
	1.96	06
	1.97	07
20	1.98	08
	1.99	09
	1.901	001
	1.902	002
	1.903	003

25 It will be noted, from the above tables, that in the case of uninterrupted service, the subscriber sends the prefix "1" before the program service number.

30 To originate an ordinary call, the subscriber removes the receiver in the usual way, causing relay L to operate: battery, winding of T₁, c₀₂, subscriber's loop c₀₁, winding of L, l_{b1}, t₁₁, earth. Relay T₁ is marginal and does not operate in series with relay L. The line relay L originates the call to the exchange equipment in the normal manner.

35 When relay Co is operated via nd₁, all the special equipment for the re-transmission of programs is disconnected from the line and dialing and conversation will take place exactly as for a normal subscriber's line.

40 If the subscriber desires to choose a program or the like, he throws key CT without removing his receiver. Earth is now connected to the following circuits in parallel (a) winding of relay A, c₁, t₁, b wire, c₀₁, winding of L, l_{b1}, t₁₁, earth. (b) winding of retard R, c₁₃, contact of dial D, c₂, a wire, c₀₂, winding of T₁, battery. Relay T₁ operates and relay L being short-circuited does not energize. Relay T₁ operates relay L_b and 45 lights lamp OL temporarily. The subscriber dials without receiving dial tone.

50 If the subscriber wants uninterrupted program service, the number will have two, three or four digits. If, on the contrary, he desires to receive incoming calls during the program, the choice will be made by numbers of one, two or three digits as will be apparent from the table set out above. Numeral 1 is used for the first digit only in the case of uninterrupted program service.

55 Let us assume that the subscriber dials for uninterrupted service. The impulse corresponding to the digit 1 releases T₁ and operates magnet SPM temporarily. At the end of the impulse, magnet SPM is released and the switch takes one step forward on to contacts 1. On the release of relay L_m which operated in parallel with magnet SPM, relay Nd energizes: earth, right hand winding of Nd, nd₂ unoperated, wiper a, l_{m1}, winding of T₁, battery. Relay Nd locks: battery, left hand winding of Nd, off normal contact ON, nd₂ operated, right hand winding of Nd, earth. Relay Nd opens its normal contact 1 thus cutting off the relay Co from the third wire of the subscriber's multiple. Contact nd₁ 60 also connects characteristics of a busy line (either

of a normal subscriber's line or the first or last of a P. B. X. group) to the third wire of the subscriber's multiple. The remaining digit or digits are then dialed. If a second digit 9, or second digit 9 and third digit 0 are included in the number, the switch rests on contacts 10 and perhaps 20 during the interdigital periods.

65 When the wanted position of the switch is reached, brushes a and b of the switch connect the subscriber's line wires to the secondary winding of transformer TS of the desired program, the primary transformer winding being connected over contacts of the operated program key SK to the program circuit PRG if the program is at the time available. The line wires are connected via c₁₁ and c₁₃ of operated key CT at the substation to the subscriber's loud speaker or amplifier.

70 If the subscriber wishes to receive telephone calls while listening to a program, he does not dial the prefix 1. Relay Nd is, therefore, not operated and an incoming call will operate the relay Co and break down the program connection. When the relay Co operates, relay A at the subscriber's station is energized via c₁₁, wire b, c₀₁ and the direct current feed from the central office. The subscriber will notice the incoming call since the program will be automatically disconnected and at the same time a visual or audible signal will be put into operation by relay A. The subscriber may then establish his connection by restoring key CT to its normal position and remove his telephone from the switch hook. The operation of relay Co on an incoming call releases relay T₁ which in turn releases L_b. Earth is now connected via t₁₁, l_{b1}, wiper c, off normal bank of the switch, interrupter contacts and winding of magnet SPM, battery. The switch now homes and on reaching its normal position stops. The program equipment is now 75 at normal. If the subscriber wishes to originate a call during interrupted or uninterrupted program service, he restores key CT to normal position. Relays T₁ and L_b are thereby released in turn and switch SPM homes. If relay Nd was 80 operated, the opening of contacts ON releases it thus re-connecting relay Co to the third wire of the subscriber's multiple. The subscriber then removes his telephone receiver, waits for dial tone or the reply of the manual operator and 85 the call is set up in normal fashion. The step-by-step program selector is automatically returned to normal each time key CT is restored to normal by the subscriber and also each time relay Co is operated as in the case of an incoming call.

90 During program selection relay Nd is not operated. By means of these circuits a subscriber can be given access to theatrophone service, radio rediffusion service, time, news service or the like. Change from one program to another can be obtained by restoring key CT momentarily, after which the number of the new service required is dialed.

95 The step-by-step switch S may be provided with a special brush e for metering purposes by means of an arrangement shown on the drawing and in which, when the transmission feeder is connected either automatically or manually by key SK to the primary winding of the transformer connecting the output circuit to the a and b brushes of the switch, the terminal of the bank of wiper e may be connected to a time impulsing device which sends impulses at given intervals to the service meter SMI connected to wiper e, which therefore will record the time and class 100

- of the selection received. In dotted lines there are shown connected to the same wiper and terminal, a wattmeter WM and a resistance to battery. This wattmeter of any approved type, may 5 indicate the duration and the class of the selection received by simply connecting a given resistance to battery to the terminal in the bank of the wiper e. The resistances or impulsing devices associated with the keys SK of different program 10 circuits may be chosen with respect to the value of the several programs so that a subscriber will be charged for the service accordingly.
- What is claimed is:
1. In a combined telephone and program distributing system, a telephone line, program service and telephone service selectable over said line, means for establishing a program service connection over said line, and means operated during the establishment of said program service 15 connection for predetermining whether or not said program service connection may be interrupted by an incoming telephone service connection.
  2. In a combined telephone and program distributing system, a telephone line, program service and telephone service selectable by the subscriber over said line, means for establishing a program service connection over said line, and means under the control of said subscriber in the 20 establishment of said program service connection to predetermine whether or not said program service connection may be interrupted by an incoming telephone service connection.
  3. In a combined telephone and program distributing system, a telephone line, program service and telephone service selectable by the subscriber over said line, means for establishing a program service connection over said line, and means under the control of said subscriber in the 25 establishment of said program service connection to at will mark said line busy or idle to selectively incoming calls.
  4. In a combined telephone and program distributing system, a telephone line, program service and telephone service selectable by the subscriber over said line, means for establishing a program service connection over said line, means under the control of said subscriber in the establishment of said program service connection 30 to place a false busy condition on said line, and means responsive to the initiation of an outgoing call to restore said program service connecting means to normal and remove said false busy condition.
  5. In a combined telephone and program dis- 35
- tributing system, a telephone line, program service and telephone service selectable by dial impulses over said line, means for establishing a particular program service connection over said line by dialing any one of a plurality of codes, and means effective in accordance with the code dialed for predetermining whether or not said program service may be interrupted by an incoming telephone service connection. 80
6. In a combined telephone and program distributing system, a telephone line, program service and telephone service selectable by dial impulses over said line, means for establishing a particular program service connection over said line by dialing any one of a plurality of codes, and means operated when said program service connection is established in response to the dialing of only a particular one of said codes for marking said line busy to incoming calls. 85
  7. In a combined telephone and program distributing system, a telephone line, program service and telephone service selectable over said line, a switch for establishing a program service connection over said line, and means operated in a particular position of said switch for preventing 90 the interruption of said program service connection by an incoming telephone service connection. 95
  8. In a combined telephone or program distributing system, a telephone line, program service and telephone service selectable over said line, a switch for establishing a program service connection over said line, and means operated in a particular position of said switch for marking 100 said line busy to incoming calls. 105
  9. In a combined telephone and program distributing system, a telephone line, program service and telephone service selectable by dial impulses over said line, a switch operable in response to one or more dialed digits to establish a program 110 service connection over said line, and means effective if said switch is operated by a particular first digit for preventing the interruption of said program service connection by an incoming telephone service connection. 115
  10. In a combined telephone or program distributing system, a telephone line, program service and telephone service selectable by dial impulses over said line, a switch operable in response to one or more dialed digits to establish 120 a program service connection over said line, and means effective if said switch is operated by a particular first digit for marking said line busy to incoming calls. 125
